UNITED STATES PATENT OFFICE

164,308

SHOE OR SIMILAR ARTICLE

Jack Macht, New York, N. Y.

Application April 10, 1951, Serial No. 14,781

Term of patent 3½ years

(Cl. D7—7)

To all whom it may concern:

Be it known that I, Jack Macht, a citizen of the United States of America, residing in New York, county of New York, and State of New York, have invented a new, original, and ornamental Design for a Shoe or Similar Article, of which the following is a specification, reference being had to the accompanying drawing, forming part thereof. The figure in the drawing is a perspective view of a shoe or similar article showing my new design. The opposite side of the shoe presents substantially the same appearance as shown.

I claim:

The ornamental design for a shoe or similar article, substantially as shown and described.

JACK MACTH.
